DESIGN FOR A MOUNTING FOR HANDBAGS OR THE LIKE

Suzanne Ray Dupuis, New York, N. Y.

Application July 12, 1941, Serial No. 102,104

Term of patent 3½ years

To all whom it may concern:

Be it known that I, Suzanne Ray Dupuis, a citizen of the Republic of France, residing at New York city, in the county and State of New York, have invented a new, original, and ornamental Design for a Mounting for Handbags or the like, of which the following is a specification, reference being had to the accompanying drawing, forming part thereof.

Figure 1 is a front elevational view of a mounting for handbags or the like showing my new design; and

I claim:

The ornamental design for a mounting for handbags or the like, substantially as shown.

SUZANNE RAY DUPUIS.
